UNITED STATES PATENT OFFICE.

HERBERT BARCROFT ODELL, OF TORONTO, ONTARIO, CANADA.

OIL BURNER.

Application filed September 2, 1924. Serial No. 735,335.

To all whom it may concern:

Be it known that I, HERBERT BARCROFT ODELL, a citizen of the United States of America, residing in the city of Toronto, 5 county of York, Province of Ontario, Canada, have invented certain new and useful Improvements in Oil Burners, of which the following is a specification.

My invention relates to improvements in 10 oil burners, and one object of my invention is to provide a contrivance of the class set forth especially adapted for domestic use to be automatic in its action in regulating the pressure of the steam jet so as to automatically control the heat generated by the 15 burner, and so make it safe for use. Another object of my invention is to prevent the fuel passing out of the oil nozzle when the burner is not in operation and in the following specification I shall describe and 20 illustrate my invention, and what I claim as new will be set forth in the claims forming part of this specification.

Fig. 1 is a side elevation of my oil burner 25 showing the pipes or conduits for the liquids and fluids used. Fig. 2 is an elevation of the left-hand end of the contrivance, showing portion of the pipes or conduits. Fig. 3 is a side elevation of the distributing head 30 to receive the air and steam and oil, and which head supports the nozzles. Fig. 4 is a plan view of said distributing head, partly shown in section, and Fig. 5 is a vertical cross section on the line 5—5, Fig. 4.

35 In the drawings, like characters of reference refer to the same parts.

2 is a hollow conical shaped steam generator provided with a central passage-way 3 therethrough. This passage-way widens 40 out from its intake end to its discharge end so that certain well-known advantages will be obtained. Since the discharge end of the said passage-way is wider than the intake end, the flame will be uniformly distributed 45 over the flame zone and consequently no one portion of any body against which the flame plays will be overheated. Another advantage obtained is that the noise of combustion is reduced to a minimum, thus removing 50 one of the objections the general public has to appliances of this class.

Water is preferably supplied to said steam generator by gravity by a tank (not shown), and the pipe 4 leads from said tank and 55 communicates with the interior of said steam generator. Any suitable control valve 5 is

provided to regulate the volume of water passing through the pipe 4. By means of the pipe 6 steam is piped from the generator 2 into the passage-way 7 formed in the distributing head 8. The passage-way 7 communicates with a passage-way 9 in the outer end of which is supported the fluid nozzle 10.

11 is a fuel-level-control bowl which communicates by the pipe 12 with a fuel tank (not shown). 13 is a pipe leading from the bowl 11 to a port 14 formed in one side of the head 8. This port communicates with a passage-way 15 formed in the foot 16 of 60 said head, and carried by said foot is the vertically-disposed oil nozzle 17 which communicates with said passage-way 15. 18 is a pipe which leads to an air pump (not shown), and at this point I should make 65 mention that since the air is used only temporarily in this contrivance while starting it, a hand-operated air pump is preferably used.

The pipe 18 is coupled to a pipe 19, which pipe is coupled to the head 8 and communicates with a passage-way 20 formed in 70 said head. The said passage-way 20 communicates with the passage-way 9 which is in communication with the fluid nozzle 10.

Associated with the pipes 18 and 19 is 75 a safety valve diagrammatically indicated at 21, and 22 is a weighted lever pivoted at 23, and co-operating with the said safety valve to control pressure of both air and steam.

When the valve 24 is opened, the fuel oil 80 will flow through the pipe 13 and port 14, and after filling the passage-way 15 it will rise almost to the top of the oil nozzle 17. Now as before-stated air is used temporarily 85 to start the contrivance, and consequently the stream of air blowing across the outer end of the nozzle 17 will carry the oil out of said nozzle and atomize it. The mixture is then ignited by a flame, and burns. The 90 said burning mixture will in due course heat the steam generator 2 and generate steam. The steam will then pass through the pipe 6 and into the passage-ways 7 and 9 and escape through the nozzle 10 and perform the function performed by the air.

Obviously it will not be necessary to use air after the steam has been generated.

It is desirous that the pressure of the steam be kept quite low, say approximately, 110 two pounds to the square inch for domestic use, and consequently I provide the safety

valve before-mentioned which will blow off in case the pressure goes above the desired amount. Since air is initially passed through the pipe 19, and since this pipe 5 communicates with the passage-ways 20 and 9; and further since the steam passage-way 7 communicates with said passage-ways, it is evident that the pipe 19 is bi-functional, because while it conveys air initially to the 10 oil burner, it performs the additional function of an exhaust for the steam when the same reaches an excessive pressure, and therefore it is necessary that a suitable safety valve, such as diagrammatically indicated at 21, be associated with said pipe 19.

Integrally formed with the head 8 is a pan *a* which surrounds the foot 16. This pan will collect any unconsumed oil that may possibly escape from the nozzle 17, and 20 consequently when this oil is ignited, the heat generated thereby will assist to keep the nozzles hot.

A removable cover *b* to house the space separating the intake end of the steam generator 2 from the head 8 is provided, and 25 in Fig. 1 it is shown clearly that one end of this cover rests upon the generator 2 and the other end rests upon the head 8.

This cover is readily removable to permit 30 the cleaning of the nozzles.

The discharge ends of the nozzles 10 and 17 are preferably located as shown in the drawings so that the stream of air or steam passing through the nozzle 10 will blow directly over the discharge end of the nozzle 35 17.

Where this contrivance is used for domestic purposes, it is advisable to have the safety valve for the steam, though it must 40 be clearly understood that I may omit this safety valve when my contrivance is used by skilled operators.

Obviously various changes in details of construction may be made without departing 45 from the spirit of my invention.

What I claim is:

1. In a contrivance of the class described, in combination a chambered steam generator having a passage-way therethrough; a 50 distributing head located in front of said steam generator and provided in its upper portion with distinct inlet passage-ways which meet in a common horizontally-disposed outlet passage-way; a fluid nozzle mounted in said last-mentioned passage-

way and projecting beyond said head and opening towards the passage-way through said generator; a foot integrally formed with said distributing head and provided with a fuel passage-way therethrough, 60 which communicates with an intake fuel passage-way formed in said head; a vertically-disposed fuel nozzle carried by said foot and opening into the fuel passage-way thereof, and having its discharge end located adjacent the discharge end of said fluid nozzle; an air pipe opening into one of said first-mentioned inlet passage-ways; a safety valve associated with said air pipe; a steam pipe leading from said steam generator and opening into the other of said first-mentioned inlet passage-ways, the excessive pressure of steam escaping through said air pipe, and a fuel-level-control bowl 70 coupled to the fuel intake of said head, the whole arranged to operate as set forth. 75

2. In a contrivance of the class described, in combination a chambered steam generator having a passage-way therethrough; a distributing head located in front of said steam generator and provided in its upper portion with distinct inlet passage-ways which meet in a common horizontally-disposed outlet passage-way; a fluid nozzle mounted in said last-mentioned passage-way and projecting beyond said head and opening towards the passage-way through said generator; a foot integrally formed with said distributing head and provided with a fuel passage-way 80 therethrough, which communicates with an intake fuel passage-way formed in said head; a vertically-disposed fuel nozzle carried by said foot and opening into the fuel passage-way thereof, and having its discharge end located adjacent the discharge 85 end of said fluid nozzle; an air pipe opening into one of said first-mentioned inlet passage-ways; a safety valve associated with said air pipe; a steam pipe leading from said steam generator and opening into the other of said first-mentioned inlet passage-ways, the excessive pressure of steam escaping through said air pipe, a fuel-level-control bowl 90 coupled to the fuel intake of said head, and a pan integrally formed with said head and associated with said foot so as to collect any unconsumed oil, the whole arranged to operate as set forth. 95

HERBERT BARCROFT ODELL.
